UNITED STATES PATENT OFFICE

2,111,472

ELASTIC KNIT FABRIC

Walter J. Horn, Philadelphia, Pa., assignor to
 William H. Horn & Bro., Incorporated, Philadelphia, Pa., a corporation of Pennsylvania

Application August 13, 1936, Serial No. 95,884

2 Claims. (Cl. 66—189)

This invention relates to elastic fabrics and particularly to a fabric for use in elastic stockings as disclosed in the prior United States Letters Patent of Charles E. Southwick, Jr., No. 5 2,015,608 dated September 24, 1935.

The stocking disclosed in the above noted patent is composed of ribbed fabric with a rubber thread inlaid in each course of the stitches of which the fabric is composed, the rubber thread 10 in the leg portion, in the foot portion and in an intermediate rear portion lying between the lower end of the leg portion and the foot portion, adjacent the heel, being held between a set of stitch wales on one face of the fabric and a second set of stitch wales on the opposite face of the fabric, with the knitting thread extending from the one to the other of said faces between the rubber strands in the respective stitch courses and connecting the two sets of stitch wales constituting the opposite faces respectively of the 20 fabric.

In an area lying intermediate the foot portion and the lower end of the leg portion, in front of the aforementioned rear portion which is disposed adjacent the heel, i. e. an area constituting the instep portion of the stocking, the above noted connecting portions of the knitting thread extend from the stitch wales on the one face of the fabric to the stitch wales on the opposite face 30 of the fabric only at alternate courses of stitches, whereby the instep portion of the stocking is foreshortened walewise of the fabric within the instep portion to give the front of the stocking a natural curvature where the stocking is required 35 to bend at the wearer's ankle.

In knitting a stocking according to the disclosure of the above noted patent the stitches of the wales on the one face of the fabric are all of a uniform size, i. e. each stitch is of a length equal 40 to the walewise width of a single course. Within the foreshortened instep area each stitch in each wale on the opposite face of the fabric is of a length equal to the walewise width of two courses of stitches.

45 With the above noted arrangement of stitches on the opposite faces respectively of the fabric, within the foreshortened instep area of the stocking, it has been found that when the stocking is produced from certain of the finer yarns of the 50 higher counts on machines of relatively fine gauges, to provide light weight stockings, the longer stitches on the one face of the fabric, which incidently is the outer face of the fabric when the stocking is being worn, have a tendency, 55 in some instances, to pucker and thereby mar

the otherwise smooth appearance of the stocking.

The object of the present invention is to provide a fabric of the same general construction as that disclosed in the above noted patent but modified in a manner to eliminate puckering, as 5 will be fully disclosed hereinafter, reference being had to the accompanying drawings wherein:

Fig. 1 is a side elevation of the stocking in a flattened form;

Fig. 2 is a front elevation of the stocking flattened in a plane at 90° to the plane of flattening in Fig. 1; and

Fig. 3 is an enlarged diagrammatic view of the fabric in the instep portion of the stocking shown 15 in Figs. 1 and 2.

As shown in Figs. 1 and 2, the stocking is composed of ribbed knit fabric and comprises an upper leg portion A and a foot portion B and which from the top edge of the portion A and the lower edge of the portion B to the course lines 20 a—a and b—b respectively are composed of usual successive stitch courses 1, 1 (see Fig. 3), each having a strand of elastic 2 laid in the fabric between the front wales 3 and the back wales 4, which are formed on different banks of needles 25 respectively as is usual in the formation of ribbed fabric.

The stitches of the wales on one face of the fabric are connected to the stitches of the wales on the opposite face of the fabric by connecting 30 portions 5, 5 of the thread of which the stitches on the opposite faces of the fabric are alternately composed, said connecting portions 5 passing through the fabric and assuming a more or less zig-zag formation between the opposite faces 35 of the fabric.

Normally the elastic strands 2 are held in the fabric by the stitches 3 and 4 on opposite faces of the fabric respectively and between the connecting portions 5 of the thread of which said stitches 40 of the successive courses are composed, said connecting portions 5 effecting a definite spacing of the elastic strands 2.

Between the lowermost course a—a of the top portion A and the topmost course b—b of the foot 45 portion B, Fig. 1, the back portion of the stocking from a wale line c—c at one side of the stocking around the back of the stocking to a corresponding wale line on the opposite side of the stocking is provided with an area C, wherein the elastic 50 strands 2 are laid in the fabric in the same manner as in the top and foot portions A and B, as above noted.

From the wale line c—c on the one side of the stocking to the corresponding wale line on 55

the opposite side of the stocking, extending around the front of the stocking, the stocking is provided with an area D, wherein the elastic strands 2, 2 are drawn closer together than in 5 the surrounding and adjacent areas A, B, and C.

The drawing of the elastic strands 2, 2 closer together in the area D and the retaining of the strands in the single general plane of the fabric is accomplished in the present case by adjacent 10 pairs of the needles which are knitting the stitch wales of one face of the fabric within the area D holding their stitches of one course during the formation of the next course of stitches by single 15 needles intermediate each of said pairs and by the needles knitting the stitch wales of the opposite face of the fabric, without the needles which are holding the stitches taking on the thread of which the next course of stitches is composed, then taking thread during the formation 20 of the next succeeding course of stitches and casting the held stitch, whereby the stitch holding needles knit at only every second course, i. e. in alternate courses on one face of the fabric, while the said intermediate needles and the set 25 of needles producing the stitch wales on the opposite face of the fabric are knitting in every course.

By the above procedure adjacent pairs of the wales 3a, 3a on the one face of the fabric, with- 30 in the area D, are composed of elongated stitches indicated at 6, 6, Fig. 3, while the wales 4 on the opposite face of the fabric and the intermediate wales 3b on the first said face of the fabric are composed throughout of normal length 35 stitches 7, 7, and 6a, 6a respectively.

By the needles forming the wales 3a, 3a on the one face of the fabric failing to take thread during the knitting of alternate courses 1a, 1a, and taking thread during the formation of the 40 intermediate courses 1b, 1b the connecting threads 5, connecting the wales 3 with the wales 4, pass through the fabric from face to face thereof during the casting of the stitches of the alternate courses 1a, 1a, but during the casting 45 of the stitches of the intermediate courses 1b, 1b the wale-connecting threads do not pass through the fabric and are held on one side of the fabric, floating coursewise across wales 3a, 3a and connecting the wales 4, 4 on the one face of the 50 fabric only, as clearly indicated at 5a, 5a, Fig. 3.

As a result of the above procedure, the elastic strands 2, 2 within the area D are drawn together in pairs, and the absence of the cross threads 5, 5, between the strands of the pairs 55 foreshortens the fabric walewise to the extent of the sum of the diameters of the number of missing cross threads and such foreshortening draws or contracts the front of the stocking relative to the back of the stocking to an extent which 60 produces the natural curvature 10 in the instep portion of the stocking.

The contracting of the front of the stocking

within the area D reacts to place the rear area C under tension walewise of the fabric. This tension is relieved and the curvature 10 is further accentuated by the provision of a heel notch 11 formed in the stocking in the usual manner and which extends across the back of the stocking from a point adjacent and to the rear of the substantially central side wale c—c at the one side of the stocking to a corresponding point at the opposite side of the stocking. 5

From the above, it will be clear that the curvature in the front of the stocking is smooth and in the single plane of the normal thickness of the fabric and lends itself readily to free bending movement of the foot at the ankle without any 10 bulkiness and without causing the wearer any discomfort. 15

While the area D has been illustrated as being substantially rectangular, it will be obvious that the contour of this area may assume any desired 20 configuration without departing from the spirit of the present invention.

The breaking up of the solid area of long 25 stitches 6 on the one face of the fabric within the area D with relatively spaced wales of regular 30 stitches 7 has been found to eliminate the puckering of the fabric as above noted without affecting the foreshortening of the fabric in the instep portion of the stocking. 35

I claim:

1. A knitted elastic bandage comprising successive courses of stitches forming two series of wales on opposite faces respectively of the fabric and connected by cross threads extending through the fabric from face to face thereof in 35 one area of the fabric at each stitch and in an adjacent area of the fabric only at spaced 40 courses at wales periodically alternating with wales having cross threads at every course with elastic strands disposed in the fabric intermediate said face wales and secured in predetermined 45 relation to each other in the general plane of the fabric by said cross threads causing a walewise foreshortening of the fabric in the second named area relative to the first said area. 50

2. A knitted elastic bandage comprising successive courses of stitches forming two series of wales on opposite faces respectively of the fabric and connected by cross threads extending through the fabric from face to face thereof in 55 one area of the fabric at each stitch and in an adjacent area of the fabric at spaced courses at wales periodically alternating in six to one order with wales having cross threads at every course with elastic strands disposed in the fabric intermediate said face wales and secured in predetermined 60 relation to each other in the general plane of the fabric by said cross threads causing a walewise foreshortening of the fabric in the second named area relative to the first said area. 65

WALTER J. HORN.
